UNITED STATES PATENT OFFICE

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

TURBINE.

1,137,704.

Specification of Letters Patent. Patented Apr. 27, 1915.

Application filed April 26, 1912. Serial No. 693,432.

To all whom it may concern:

Be it known that I, CHARLES W. DAKE, a citizen of the United States, residing at Chicago, in the county of Cook and State of Illinois, have invented a certain new and useful Improvement in Turbines, of which the following is a specification.

My invention relates to improvements in turbines, and is illustrated in one form in 10 the accompanying drawings, wherein—

Figure 1 is a transverse section; Fig. 2, a section on the line S—S of Fig. 1; Fig. 3, a diagrammatic view of the rotor rim with the inlet shown on the dotted line X of 15 Fig. 1; Figs. 4 and 5, details.

Like parts are indicated by the same number in all the figures.

1 is one side and 2 the other side of the rotor case; 16 is an opening in the rotor case closed by the cap 17 which contains the inlet channel 15 and into which is screw-threaded the inlet tube 3. From the inner end of the inlet channel leads the inlet nozzle 14; 4 is the exhaust outlet; 5 is a shaft 20 which passes through a central opening in one side of the case and carries at its inner end the rotor body 6 about the periphery of which is formed the ring 7 into which is secured in any desired manner the channel 25 pieces 8 and 9. These pieces and the ring are spaced by and connected together through the diagonally placed spacing blocks 11 which are provided as shown with holes for both the screws; 12 and 13 are U-shaped 30 annular grooves formed by and between the channel pieces and the ring. The nozzle 14 is placed so as to discharge the fluid at a sharp angle to the radius of the rotor, has diverging walls and extends beneath the 35 overhanging ring on the periphery of the rotor body. The edges of the channel pieces are sharpened and the edge of the ring inclined so as to make each channel opening larger in cross section than the body of the 40 channel. The rotor shaft is mounted in any desired manner, the bearings not being 45 here shown, and the body may be of any desired shape, although it is here shown as a

disk. The ring and channel pieces together constitute the rim of the rotor. I have shown 50 two channels; there might be one or more than two. I have shown the connection between the exhaust and the rotor as made at a single point by means of an over-hanging ledge, but of course the connection can be 55 made in any desired way.

It will be understood, of course, that I have omitted parts which will have to be understood as present, for example, bearings for the rotor shaft, that the parts as actually 60 shown are not necessarily made in the exact proportions and relations indicated, that some of them may be dispensed with and others substituted, and that considerable variation can be made in the size, shape, 65 proportions and arrangements of the several parts all without departing from the spirit of my invention. The drawings are to be taken in a certain sense as diagrammatic.

The nozzle 14 is placed at a sharp angle 70 to the radius of the rotor, has outwardly diverging walls and extends beneath the overhanging ring on the periphery of the rotor body. The edges of the channel pieces are 75 grooved and the edge of the ring inclined so as to make each opening of each groove larger in cross section than the body of the groove or channel.

The use and operation of my invention are as follows: Assuming that the parts are 80 constructed and arranged substantially as indicated in Fig. 1, if a fluid under pressure, for example steam, be introduced through the inlet, it will discharge through the expanding nozzle into the enlarged 85 openings of the channels on one side of the rotor, will then pass inwardly through and diagonally along the two channels and across the periphery of the rotor and forwardly in the direction in which the rotor 90 is moving from the inlet to the discharge side of the rotor casing and will ultimately pass out of the channels at practically 95 rotor speed into the exhaust side of the case and thence into the exhaust. The streams of fluid will pass on both sides of the spac-

ing blocks which are set so as to cause the least possible interference. The fluid in being thus diverted from a direct passage through the channel or being directed 5 against the curved wall of the channel, will tend to have its pressure increased along or between the curved wall of the channels. This, however, re-acts to increase the friction on the walls of the channels and thus 10 to transmit more thoroughly and completely the energy in the fluid to the rotor rim to cause the rotor to rotate. The fluid travels with the rim and if the parts are properly designed most of the fluid will escape on the 15 exhaust side of the rotor into the exhaust at approximately the opposite end of the diameter of the rotor, at the other end of which the fluid is admitted. Broadly speaking the fluid is fed into a narrow space be- 20 tween two surfaces or into a channel bounded by two surfaces, and these surfaces are arranged, as for example curved, so as to deflect or divert the current or currents of fluid from a direct course to an indirect 25 course, thus arresting the forward progress of the fluid and diverting an increased friction for the purposes set out. The partic- 30 ular method of thus diverting or changing the direction of the current or currents of fluid on the passage through the open channel or channels may not be just what is here shown, but what I have shown appears to be an easy and convenient method or apparatus for accomplishing this result.

35 I claim:—

1. In a turbine a rotor having an annular smooth-surfaced channel with means for dis- 40 charging a driving fluid thereinto in a di- 45 rection inclined to the tangent thereto at the point of impingement so as to rotate the rotor by frictional contact with said fluid, and means for increasing the total pressure of the fluid within said channel upon the walls thereof.

45 2. In a turbine a rotor having a series 50 of annular smooth-surfaced channels with means for discharging a driving fluid there- 55 into in a direction inclined to the tangent thereto at the point of impingement so as to 60 rotate the rotor by frictional contact with said fluid, and means for increasing the total pressure of the fluid within said channels upon the walls thereof.

55 3. In a turbine a rotor having an annular smooth-surfaced channel with means for dis- 60 charging the driving fluid thereinto so as to rotate the rotor by frictional contact with said fluid, and means for increasing the total pressure of the fluid within said chan- 65 nel upon the walls thereof, said means con- 70 sisting in shaping the channel so as to change the course of the fluid therethrough.

4. In a turbine a rotor having a series 75 of annular smooth-surfaced channels with

means for discharging the driving fluid 80 thereinto so as to rotate the rotor by frictional contact with said fluid, and means for increasing the pressure of the fluid within 85 said channels, said means consisting in shaping the channels so as to change the course 90 of the fluid therethrough.

5. In a turbine the combination with a case, a rotor having a shaft a body and a rim, the latter containing a U-shaped an- 95 nular channel so as to retard the flow of 75 fluid therethrough and a fluid inlet discharging into said channel in a direction inclined to the tangent to the channel at the point of impingement at the point of discharge.

6. In a turbine the combination of a case, 80 a rotor having a shaft a body and a rim, the latter comprising an under-cut ring, a series of annular channel pieces and a series 85 of diagonally set spacing blocks between the ring and the channel pieces to form a series 90 of U-shaped annular channels, said channel pieces sharpened at their edges and the ring beveled so as to make the two openings of each channel wider in cross-section than the body of the channel, a fluid inlet nozzle ex- 95 panding and projecting behind the ring and adapted to discharge into the channels at one end of and sharply inclined to a rotor diameter and a discharge outlet at the other end of such diameter. 95

7. In a turbine the combination of a case, 100 a rotor having a shaft a body and a rim, the latter comprising a series of annular channel pieces and a series of diagonally set spacing blocks between the ring and the channel 105 pieces to form a series of U-shaped annular channels, said channel pieces sharpened at their edges so as to make the two openings of each channel wider in cross-section than the body of the channel, a fluid inlet nozzle 110 expanding and adapted to discharge into the channels at one end of and sharply inclined to a rotor diameter and a discharge outlet at the other end of such diameter. 110

8. In a turbine the combination of a case, 115 a rotor having a shaft a body and a rim, the latter comprising a series of annular channel pieces mounted so as to form a series of U-shaped annular channels, a fluid inlet nozzle 120 adapted to discharge into the channels at one end of and sharply inclined to a rotor diameter.

9. In a turbine the combination of a case, 125 a rotor having a shaft a body and a rim, the latter comprising a series of annular channel pieces mounted so as to form a series of U-shaped annular channels, a fluid inlet nozzle adapted to discharge into the channels at one end of and sharply inclined to a rotor diameter and a discharge outlet from the 130 case.

10. In a turbine the combination of a case, 135 a rotor having a shaft a body and a rim, the

latter comprising a series of annular channel pieces mounted so as to form a series of U-shaped annular channels, a fluid inlet nozzle adapted to discharge into the channels 5 at one end of and sharply inclined to a rotor diameter and a discharge outlet from the case approximately at the other end of such diameter.

11. In a turbine the combination of a case, 10 a rotor having a shaft a body and a rim, the latter containing a series of U-shaped annular channels and a fluid inlet discharging into said annular channels on one side of the rotor at an angle to the rotor radius at the 15 point of such discharge.

12. In a turbine the combination of a case, 20 a rotor having a shaft a body and a rim, the latter containing a series of U-shaped annular channels and a fluid inlet discharging into said channels on one side of the rotor said channels open so that the fluid may escape on the other side of the rotor.

13. In a turbine the combination of a case, 25 a rotor having a shaft a body and a rim, the latter containing a series of U-shaped annular channels and a fluid inlet discharging into said channels on one side of the rotor said channels open so that the fluid may escape on the other side of the rotor said 30 discharge at an angle to the rotor radius at the point of such discharge.

14. A turbine comprising a rotor with a series of U-shaped annular channels about the periphery thereof and means for dis- 35 charging a driving fluid through said channels from one side of the rotor to the other and forwardly in the direction of rotation.

15. In a turbine an annular rotor inwardly channeled continuously about the inner side thereof and means for directing a 40 motive fluid stream diagonally into said channel along one wall thereof in a plane perpendicular to the axis of rotation.

16. In a turbine a rotor having an annular 45 inwardly open channel about the periphery thereof and means for discharging a motive fluid stream into said channel outwardly along one wall thereof in a direction inclined to the tangent thereto and in 50 a plane perpendicular to the axis of rotation thereof.

17. In a turbine a rotor having an annular 55 inwardly open channel about the periphery thereof, means for discharging a motive fluid stream into said channel outwardly along one wall thereof in a direction inclined to the tangent thereto and in a plane perpendicular to the axis of rotation thereof and means for guiding said stream about 60 the inside of said channel and discharging it therefrom along the opposed wall in a plane parallel with the plane of its entrance to the channel.

18. In a turbine an annularly channeled

65 rotor, said channel opening inwardly toward the axis of rotation and being semicircular or U-shaped in cross section, means for diagonally directing a stream of motive fluid into and against the wall of said channel along one side thereof and discharging said 70 fluid inwardly from said channel along the opposed wall thereof in planes perpendicular to the axis of rotation.

19. A turbine having a rotor, a continuous 75 smooth-surfaced annular bucket substantially U-shaped in cross section extending about the periphery thereof, means for discharging a stream of motive fluid against said bucket in a plane perpendicular to its axis of rotation and inclined to a tangent 80 thereof, and means for discharging said stream of material in a similar plane from the opposed side of the bucket.

20. In a turbine an annularly channeled 85 rotor, said channel having two parallel walls and a curved wall joining them and means for directing a motive fluid into said channel along one wall in a plane perpendicular to the axis of rotation thereof and guiding it down into and along the curved 90 wall and out inwardly from the channel along the opposed wall.

21. In a turbine a rotor having an annular 95 smooth-surfaced channel, means for directing a motive fluid into said channel in a direction inclined to the tangent thereto and means comprising a portion of said channel for increasing the total pressure of said stream against said channel.

22. In a turbine a rotor having an annular 100 smooth-surfaced channel, means for directing a motive fluid into said channel in a direction inclined to the tangent thereto and means comprising a portion of said channel for increasing the total pressure of said 105 stream against said channel, said means being adapted to reverse the movement of said motive fluid stream.

23. A rotor for turbines and the like comprising a series of annular smooth surfaced 110 channel members and means for directing a motive stream diagonally into said channel members along one wall of each in a plane perpendicular to the axis of rotation.

24. A rotor for turbines and the like comprising a series of annular smooth surfaced channel members and means for directing a motive stream diagonally into said channel members along one wall of each in a plane 115 perpendicular to the axis of rotation in a direction inclined to the tangent thereto.

25. A rotor for turbines and the like comprising a series of annular smooth surfaced channel members and means for directing a motive stream diagonally into said channel 120 members along one wall of each in a plane perpendicular to the axis of rotation, means for guiding said stream along the inside of

each channel and discharging it therefrom along opposed walls thereof in a plane parallel with the plane of its direction to the channel.

26. A turbine comprising a rotor of a smooth annular channel about the periphery thereof and means for discharging a driving motive fluid through said channel from one side of the channel diagonally toward the

other side of the channel while the motive fluid is traveling peripherally about the axis of rotation.

Signed at Chicago, Illinois, this 23rd day of April, A. D. 1912.

CHARLES W. DAKE.
